(57) **CLAIM**

We claim the ornamental design for a support frame for a positive pressure blower, as shown and described.

DESCRIPTION

FIG. 1 is a right rear perspective view of a support frame for a positive pressure blower showing our new design; FIG. 2 is a left rear perspective view thereof;

FIG. 3 is a front elevational view thereof;

FIG. 4 is a rear elevational view thereof;

FIG. 5 is a left side elevational view thereof; and

FIG. 6 is a right side elevational view thereof.

FIG. 7 is a bottom plan view thereof;

FIG. 8 is a top plan view thereof; and,

FIG. 9 is a tilted rear elevational view thereof.

The broken lines shown in the figures are for the purpose of illustrating environment and form no part of the claimed design.
